UNITED STATES PATENT OFFICE

2,429,845

VELOCIPEDE

Charles E. Scoles, Columbus, Ohio

Application October 26, 1944, Serial No. 560,398

1 Claim. (Cl. 280—1.19)

1

This invention relates to velocipedes, having particular reference to toy velocipedes of the type embodying a wheeled base formed with a propelling axle, the base effecting the support of an oscillatory rider-seating structure, whereby through rocking motion of the structure, imparted by the manual efforts of the rider, rotary motion is imparted to the propelling axle and its associated wheels to advance the velocipede linearly over a pavement, floor or other supporting surface.

It is an object of the invention to provide an improved velocipede of this type in which the oscillating rider-seating structure is in the form of a hobbyhorse, the same being mounted for rocking movement on a four-wheeled base frame, and wherein the construction is such that a rider, seated on the hobbyhorse, may rock the latter to impart propelling motion to at least one set of the frame-carried wheels.

While velocipedes of this general character have been proposed in the prior art, yet, nevertheless, their use and public acceptance have been restricted. It is believed that this situation is attributable in most part to the structural complexity, relatively high cost and inferior mechanical designs of the apparatus heretofore proposed.

In the construction of such velocipedes, it is deemed to be a matter of prime importance to provide between their wheeled base frames and the oscillatory rider-structure a proper form of pivotal union which will provide for ready rocking motion on the part of the seating structure, one which will be stable when the weight of the rider is imposed thereon and at the same time simple, practical and efficient in construction. Therefore, it is a particular object of the present invention to provide in a velocipede of the type set forth a novel system of link members for fulfilling this necessity and wherein the link members comprise crossed pairs which at their upper ends are pivotally connected with the seating structure and at their lower ends with the wheeled base frame.

Another object of the invention resides in the provision of improved means for steering the vehicle and in other means for transmitting the motion of the rockable seating structure to the propelling axle of the vehicle.

For a further understanding of the invention, reference is to be had to the following description and the accompanying drawings, wherein:

Fig. 1 is a side elevational view of a velocipede formed in accordance with the present invention;

Fig. 2 is a horizontal sectional view taken on

the plane indicated by the line 2—2 of Fig. 1, disclosing in plan the construction of the wheeled base frame;

Fig. 3 is a perspective view of the base frame, the seating structure supporting link members and the front wheel steering mechanism;

Fig. 4 is a vertical transverse sectional view on the line 4—4 of Fig. 1;

Fig. 5 is a similar view on the line 5—5 of Fig. 2.

Referring more particularly to the drawings, the numeral 10 designates the wheeled base frame of my improved velocipede. In the present instance, this frame comprises a pair of longitudinally extending bars 11 which are bent or otherwise fashioned to provide relatively elevated intermediate portions 12 and downwardly and outwardly bent end portions 13. These end portions are bolted or otherwise secured to front and rear axles 14 and 15, respectively.

20 Bolted to the intermediate portions 12 of the frame bars are ear members or brackets 16, and pivotally connected, as at 17, to the latter are the lower ends of spaced pairs of link members 18. A crossed pair of these members is arranged immediately above each of the bars 11 and the upper ends of the same are pivotally connected as at 19 to brackets 20 secured to the under part of the oscillatory rider-seating structure 21. By way of illustration, this structure may be in the form of a hobbyhorse, although it will be understood that such design is optional and may be greatly varied. The pivots 17 and 19 are arranged in vertical registration and in the center of gravity of the velocipede, so that the seating structure 21 may be readily oscillated by the rider and at the same time the structure will be strong, stable and relatively inexpensive to produce.

40 The rear axle 15, which in this instance is the propelling axle of the vehicle, has a set of rear wheels 22 fixed to the ends thereof for rotation in unison with said rear axle. The center of said axle is formed with a crank 23 which is detachably connected with the lower end of a connecting rod 24, the upper end of said rod being pivotally united as at 25 with the seating structure 21, whereby when the latter is oscillated back and forth through the manual efforts of the rider, the rear axle will be rotated to impart corresponding motion to its wheels 22, thus effecting the propulsion of the vehicle. While I employ the connecting rod as a simple and convenient construction for transferring motion from the seating structure to the rear axle, nevertheless, it will be understood that various other types of motion-transmitting means may be utilized.

In order that the rider may steer the vehicle, the front axle 14 carries bell crank levers 26. Each of these levers includes a wheel spindle 27 for the rotatable reception of one of a pair of front wheels 28. The levers 26 are pivoted as at 29 on the outer ends of the front axle 14, and the rearwardly extending portions of said levers are pivotally connected as at 30 with a steering bar 31, the latter extending parallel to the front axle and immediately to the rear thereof.

The center of the bar 31 includes a forwardly projecting tongue 32 which carries a fixed stud 33, the latter being slidably received in an elongated slot 34 provided in the rearwardly directed extension 35 of a turnable bracket 36. This bracket is pivotally mounted as at 37 on the center of the front axle 14, the said bracket being formed with a pair of upstanding ears 38 to which are pivoted, as at 39, the forward ends of a pair of bar members 40. At their rear ends, the bar members are united with a universal joint 41 and connected with one of the coupling members of this joint is an upwardly directed rod 42. The upper end of the rod 42 is also united with a second universal joint 43 which is arranged in the lower part of the seating structure 21. From the joint 43, a second rod 44 extends upwardly and is journaled for rotation in the seating structure, the extreme upper end of the rod 44 being joined with a transversely extending horizontally disposed cross handle 45, which is adapted to be grasped by the rider of the vehicle.

It will be seen that by turning the rod 44, corresponding motion will be imparted to the rod 42, the universal joints 41 and 43 being utilized to compensate for the rocking motion of the seating structure with respect to the base frame. The rotation of the rods 42 and 44, through the bar members 40, turns the bracket 36, the latter moving with it the steering bar 31 and wheel-carrying bell cranks 26. The forward portions of the frame bars 41 carry adjustable foot rests 46.

It will thus be seen that the present invention provides a toy velocipede of simple, practical and efficient design and one which is devoid of the structural complexity found in many prior art structures. The particular advantage which I consider my invention to bear over earlier devices of this nature is to be found in the arrangement of the crossed link members 18. These members allow for easily executed and balanced

motion of the hobbyhorse, so that the vehicle is unusually stable, embodying high mechanical strength and structural simplicity. It is obvious, however, that various modifications may be made in the construction shown in the drawings and above particularly described within the principles and scope of the invention as defined in the appended claim.

I claim:

- 10 In a velocipede of the character described, a base frame, an oscillatory rider-seating structure arranged above said base frame, a front axle stationarily secured to the forward end of said base frame, bell crank levers having wheel spindles 15 pivotally secured to the outer ends of said axle, said spindles being formed for the rotatable reception of ground-engaging steering wheels, a steering bar pivoted at its ends to said levers, a bracket pivotally mounted on the intermediate 20 portion of said front axle, said bracket being formed with a rearwardly projecting extension, a stud carried by said steering bar and having the shank thereof slidably received in an elongated slot formed in said bracket extension, a steering 25 rod rotatably journaled in said seating structure, a second steering rod, a universal joint uniting the adjoining ends of said rods, rearwardly extending bar members pivotally secured by their front ends to said bracket, and a second universal 30 joint uniting the rear ends of said bar members with the lower end of said second-named rod.
